UNITED STATES PATENT OFFICE.

CHARLES J. VAN DEPOELE, OF CHICAGO, ILLINOIS.

ELECTRO-MAGNETIC RAILWAY-BRAKE.

SPECIFICATION forming part of Letters Patent No. 367,685, dated August 2, 1887.

Application filed February 8, 1887. Serial No. 226,954. (No model.)

To all whom it may concern:

Be it known that I, CHARLES J. VAN DEPOELE, a citizen of the United States, residing at Chicago, in the county of Cook and State of Illinois, have invented certain new and useful Improvements in Electro-Magnetic Railway-Brakes, of which the following is a specification, reference being had therein to the accompanying drawings.

10 The present invention relates to improvements in electro-magneto railway-brakes of the class in which a solenoid is used to draw in a plunger and thereby actuate the brake mechanism.

15 The details of construction and operation of my invention will be hereinafter fully set forth.

In the accompanying drawings, Figure 1 is a plan view of the running-gear of a street-railway car. Fig. 2 is a side elevation, partly 20 in section, of the device shown in Fig. 1. Fig. 3 is an elevation, partly in section, showing the construction of the electro-magnetic brake-cylinder. Fig. 4 is a modification of the cylinder shown in Fig. 3.

25 Similar letters denote like parts throughout.

A represents the track, B the wheels, and C the brake-beams, which are supported in the usual or any well-known manner, and provided with shoes D, bearing against the peripheries 30 of the wheels B. Under the center of the car, preferably between the wheels B B, is pivoted a lever-arm, E, which is formed at one end with an arc-shaped extension, e, its other end being connected to a retracting-spring, F. Brake-levers f are pivotally connected to the 35 brake-beams and coupled together at their lower extremities by a longitudinal rod, G. The upper ends of the brake-levers f are then connected to opposite portions of the lever E by rods H and I, so that when the lever E is moved in one direction the rods H and I and 40 brake-levers will be drawn toward each other and the brake-shoes applied to the wheels, and when allowed to move in the opposite direction, in response to the action of the retracting-spring F, the shoes will be moved and held 45 away from the wheels.

So far I have described only the brake system shown in Figs. 1 and 2, which is substantially that in use on ordinary street-cars—that is, with hand-connections; but I wish it to be

55 distinctly understood that I do not limit myself to any particular form of brake mechanism, since so many devices are and have been used to communicate the force of the prime motor to the brake-shoes against the wheels, and I propose to use any system to which my improved electro-magnetic apparatus is applicable—for example, the apparatus heretofore described by me and covered by Letters Patent Nos. 324,894 and 347,904.

60 Instead of using an ordinary solenoid for the purpose of actuating the brake mechanism, I use a device of greatly-increased power, which is constructed as follows: A brass tube, M, which will readily receive the plunger or piston O, is formed with a number of longitudinal slots, m, and then provided with a large heavy coil of insulated copper wire, Q. So far the arrangement is substantially that of 65 other inventors; but I further provide my motor device with a thick strong iron shell, R, which may be formed with lugs r, for the purpose of securing it in working position. The inner ends of the shell R are preferably screw-threaded, as indicated, and are formed to receive heavy iron end pieces, S T, which are likewise screw-threaded, and thereby firmly secured in position, completely inclosing and firmly holding and protecting the coil Q, and 70 at the same time the magnetic force of the coils is largely augmented by the presence of the iron, which forms a very strong magnet and acts powerfully upon the iron plunger O, which, if desired, may be formed with an enlarged 75 end or extension, t, for the purpose of increasing the power of the magnet.

In Fig. 4 is shown a modification of the magnetic brake-cylinder, in which two shorter coils are used instead of one. The cylinder 80 R, just described, is made somewhat longer. A piece of iron is placed centrally within the cylinder and forms a powerful magnet. Both of the end pieces, T T', are apertured to receive the iron pistons or plungers O O', which, 85 when the device is in operation, are similarly attracted toward the central portion, V. The construction is otherwise similar to that already described, the terminals P N of the coils Q Q being connected with the source of electricity in any suitable or convenient manner. The piston or plunger O is connected to a flexi- 90 95 100

ble metallic strip or chain, W, which extends to and passes around the arc-shaped extension e of the pivoted lever E, by which the power developed in the magnetic cylinder is applied 5 to the brake system. The retracting-spring F will of course be of a sufficient strength to withdraw the plunger from the cylinder and release the wheels from the brakes whenever the current flowing in the coils Q is less than 10 sufficient to apply the brakes. The double-acting cylinder shown in Fig. 4 will be found very convenient for application where double-acting air-brake cylinders have been used.

Having described my invention, what I 15 claim, and desire to secure by Letters Patent, is--

1. In a magnetic railway-brake, the combination, with a system of brakes, of a magnetic cylinder formed of a solenoid inclosed by an 20 iron casing having iron ends, an iron plunger working in said cylinder, and connections, substantially as described, between the plunger and the brake-system, as set forth.

2. In a magnetic railway-brake, a brake- 25 actuating cylinder formed of a centrally-slotted brass tube, an iron plunger fitting thereinto,

a solenoid placed over said tube, an iron cylinder covering the tube and solenoid, and iron ends fitting into the cylinder and inclosing the central tube and the solenoid, substantially as 30 shown and described.

3. In an electro-magnetic railway-brake, a solenoid composed of a non-magnetic cylinder upon which properly-disposed helices or insulated conductors are wound, an iron exterior 35 covering and end pieces, and an iron plunger arranged to be movable in the interior non-magnetic cylinder, and connections, substantially as described, between the plunger and the brake mechanism, as set forth.

4. In an electro-magnetic railway-brake, the combination, with the actuating-solenoid, of a plunger connected to the brake system and formed with an extended portion of magnetic material attached thereto, substantially as de- 40 45 scribed.

In testimony whereof I affix my signature in presence of two witnesses.

CHARLES J. VAN DEPOELE.
